Primary Examiner — Rhea Shields(57) **CLAIM**

The ornamental design for a low profile wiring extension, as shown and described.

DESCRIPTION

FIG. 1 is a left side view of a low profile wiring extension showing my new design;

FIG. 2 is a right side view of the low profile wiring extension;

FIG. 3 is a front view of the low profile wiring extension;

FIG. 4 is a rear view of the low profile wiring extension;

FIG. 5 is a top view of the low profile wiring extension;

FIG. 6 is a bottom view of the low profile wiring extension;

FIG. 7 is a top front side perspective view of the low profile wiring extension; and,

FIG. 8 is a cross-sectional view of the low profile wiring extension taken along line 8-8 of FIG. 7.

In the drawings, the broken lines are for the purpose of illustrating environment only and form no part of the claimed design.
